UNITED STATES PATENT OFFICE.

ERNEST B. THURSTON, OF TOLEDO, OHIO, ASSIGNOR TO THE HAUGHTON ELEVATOR AND MACHINE COMPANY, OF TOLEDO, OHIO, A CORPORATION OF OHIO.

ALTERNATING-CURRENT ELECTROMAGNET.

1,352,926.

Specification of Letters Patent. Patented Sept. 14, 1920.

Application filed April 24, 1917. Serial No. 164,310.

To all whom it may concern:

Be it known that I, ERNEST B. THURSTON, a citizen of the United States of America, residing at Toledo, Lucas county, Ohio, have 5 invented new and useful Alternating-Current Electromagnets, of which the following is a specification.

This invention relates to effecting travel of members from alternating electric current 10 source.

This invention has utility for magnetic actuation of members from remote control source, especially for quieting the throw thereof.

15 Referring to the drawings:

Figure 1 is a diagram showing the voltage phase relations with the air gap open between two magnetic members, the flux therebetween being established from alternating 20 current source of electric supply in the combination of the invention herein disclosed;

Fig. 2 is a second parallelogram differing from the first in that the air gap in the magnetic circuit has been reduced, thereby 25 changing the effective phase relations;

Fig. 3 is a graph illustrative of comparative conditions as disclosed in the parallelograms of Figs. 1 and 2 as to the invention herein; and

30 Fig. 4 is a wiring diagram of an embodiment of the invention.

The members 1 and 2 are magnetic with the air gaps 3 therebetween normally maintained by the gravity of the member 2 or as 35 further assisted by the spring 4. The relative travel between the members 1 and 2 is limited by the member 5 and is such that, with the air gaps 3 open to a maximum, the flux between the members 1 and 2 is determined in that it is across such air gaps.

A source of alternating current, as the generator 6, may supply through the line 7 to the coil 8 electrical energy for establishing the magnetic flux between the members 1 and 2 for causing the member 2 to be lifted in the alternating electric circuit coil 8 and thereby reduce the air gaps 3.

In series with this coil 8 is the non-inductive resistance 9.

50 Referring to Fig. 3 and considering the line 10-11 as the length of the air gap and the line 10-12 as the pull affecting the member 2, the line 13 may be the opposing action of gravity in holding member 2 spaced from member 1, or its normal condition means

for opposing travel of the member 2 as supplemented by the spring 4.

Were the normal alternating current line voltage from line 7 to pass directly through the coil 8 without the resistance 9, the full 60 initial effect on the line voltage would be illustrated by the curve 14, 15, 16, with the considerable pull at the starting point 14. The section 14-15 represents the solenoid pull and the section 15-16 the magnetic 65 pull to sealing position. The drop in the magnetic pull from point 14 is due to the decrease in the reluctance of the magnetic circuit, which reluctance decreases because the air gap is reduced. As the members move 70 into contacting or close to contacting relation, the acceleration curve 14, 15, due to the decreased reluctance of the magnetic circuit action rapidly builds up to its maximum at the closed position. 75

Accordingly, the action of the acceleration curve between the points 14, 15, is one of decreasing acceleration, which, in the instance of throwing members, as switches, brakes, etc., tends to give the members such a 80 pull that they may be thrown ahead of the acceleration and result in a pound, disastrous to the apparatus.

By the device of this disclosure the foregoing disadvantages are automatically overcome and there is created a pick-up for the member to be moved which is of an acceleration, preferred as having a curve with no decreasing action. This end is attained by introducing the non-inductive resistance 9 90 which, in coacting with the air gaps 3, may cause initially impressed voltage 17, 18, on the coil 8 to act as shown in Fig. 1 at the angle 18, 17, 19, as to the impressed voltage 17, 19, on the resistance 9. This wide angle 95 of the starting voltages reduces the effective voltage of 17, 20. Taking this as the minimum effective voltage, it may be illustrated by the point 21 on the curve 21, 22, 23, Fig. 3.

As the air gap is reduced, the angle between the phase of the resistance 9 and the phase of coil 8 is increased with the resultant shortening of the effective action of the resistance 9, say as shown by the line 24, 25, Fig. 2, permitting the constant voltage 24, 105 26, to materially increase the effective voltage 24, 27, of the coil 8 as the air gap is shortened and moving say toward the point 22 on the curve 21, 22, 23.

There is accordingly provided a magnet 110

having an acceleration for relative travel in reducing the air gaps 3. The curve of this acceleration has less dip than the curve 14, 15, 16. This acceleration curve preferably 5 has its point 22 not less than the point 21, although the point 21 may be less than the point 22. This curve 21, 22, 23, shows the point 21 taking hold above the line 13 to overcome the condition of rest of the magnet. 10 With very short travel for the magnet member, say less than one-half inch, this taking hold of the member and pulling it with a force which is not letting the member get away, brings the full thrown position into 15 quick action for positive holding, there being entire throw in an effective and quiet manner. The action of the resistance 9 is automatically decreasingly effective more during the solenoid pull, and is of little effect during the 20 magnetic or sealing pull.

What is claimed and it is desired to secure by Letters Patent is:

1. A pair of magnetic members providing an air gap therebetween and having means 25 normally tending to keep the members apart, an alternating electric circuit coil having its voltage and current out of phase for establishing a magnetic flux through said members, and resistance means in series with said 30 coil having its voltage and amperage in phase.

2. A pair of normally spaced magnetic members, an alternating electric circuit coil for establishing a magnetic flux through 35 said members to reduce the spacing therebetween, and non-inductive means having its resistance at an angle to the resistance of the first coil.

3. A pair of normally spaced magnetic 40 members, an alternating electric circuit coil for establishing a magnetic flux through said members to reduce the spacing therebetween, and non-inductive resistance means in series with the coil having the phase of its resistance at an angle to the phase of the coil.

4. A pair of normally spaced magnetic members mounted for relative travel toward each other, an alternating electric circuit coil for establishing a magnetic flux through 50 said members to reduce the spacing therebetween, and means having its voltage phase in phase with the amperage of said means and at an angle to the voltage phase of the coil.

5. A pair of normally spaced relatively 55 movable magnetic members disposed for magnetic flux therebetween, an alternating electric circuit coil, and means having its amperage in phase with its voltage and its voltage phase angle as to the voltage phase of the coil varied as the members move.

6. A pair of normally spaced relatively 65 movable magnetic members disposed for magnetic flux therebetween, an alternating electric circuit coil, and electric means hav-

ing its voltage phase angle as to the voltage phase of the coil increased as the members approach:

7. A pair of normally spaced relatively 70 movable magnetic members, an alternating electric circuit coil for establishing a flux between the members, a source of constant voltage current supply, and resistance means in series with said coil and supply, the voltage of said means decreasing as the members approach. 75

8. A pair of normally spaced magnetic members, an alternating electric circuit coil for establishing a flux between the members, and non-inductive resistance in series with 80 said coil and governed by said flux to approach a minimum as the members approach sealing position, whereby at sealing of the members holding action of the coil is at a maximum.

9. A pair of relatively movable magnetic members having magnetic flux therebetween, there being first means opposing movement of such members toward each other and second means opposing the action of the first means, said second means including a current coil for establishing magnetic flux between said members and coacting resistance means in series with the coil having its effective resistance approach a minimum as 95 magnetic flux between the members reaches a maximum, thereby gradually increasing pull of the members toward each other above the opposing action of the first means.

10. A pair of magnetic members having 100 actuating coil means for a solenoid pull and a magnetic pull, and non-inductive means, in series with the coil means acting during the solenoid pull.

11. An alternating current circuit, an electro-magnet in said circuit including an inductive resistance coil, a non-inductive resistance in series with said coil and relatively movable magnetic circuit providing members having an air gap therebetween 110 which members in approaching sealing position decrease the voltage of the non-inductive resistance.

12. An alternating current circuit, an electro-magnet in said circuit including an inductive resistance coil, a non-inductive resistance in series with said coil and relatively movable magnetic circuit providing members having an air gap therebetween in said coil, which members in approaching sealing 120 position decrease the voltage of the non-inductive resistance.

13. The method of modifying the action of an electric circuit on a pair of spaced magnetic members comprising magnetizing 125 a circuit in which said members are included by an electric current coil and dampening the action of said coil in the relative movement of the members by a non-inductive resistance having its voltage phase at an an- 130

gle to the voltage phase of the coil, and decreasing said voltage of the resistance as the members approach sealing position by the increase of the magnetic flux in said members.

14. The method of alternating electric current control including placing an induc-

tive and a non-inductive resistance in series and varying the coacting effect of the non-inductive resistance by changing magnetic flux at the inductive resistance.

In witness whereof I affix my signature.

ERNEST B. THURSTON.
